DESIGN FOR AN ASHTRAY

Edward Robert Spiegel, Dallas, Tex., assignor of one-half to Gordon G. Guiberson, Dallas, Tex.

Application June 26, 1936, Serial No. 63,509

Term of patent 3½ years

To all whom it may concern:

Be it known that I, Edward Robert Spiegel, a citizen of the United States of America, residing at Dallas, in the county of Dallas and State of Texas, have invented a new, original, and ornamental Design for Ashtrays, of which the following is a specification, reference being had to the accompanying drawing, forming part thereof.

I claim:

The ornamental design for an ashtray, as shown.

EDWARD ROBERT SPIEGEL.
